(57) **CLAIM**

The ornamental design for a threaded head dowel, as shown and described.

DESCRIPTION

FIG. 1 is a top, front, right isometric view of the threaded head dowel showing our new design;

FIG. 2 is a bottom, rear, left isometric view thereof;

FIG. 3 is a front view thereof;

FIG. 4 is a right side view thereof;

FIG. 5 is a rear view thereof;

FIG. 6 is a left side view thereof;

FIG. 7 is a top view thereof;

FIG. 8 is a bottom view thereof;

FIG. 9 is a cross-sectional view of FIG. 3 taken about line 9-9;

FIG. 10 is top, front, right isometric view of the threaded head dowel shown in FIGS. 1-9 in an environment with a coral reef screw;

FIG. 11 is a bottom, rear, left isometric view of FIG. 10;

FIG. 12 is a front view thereof;

FIG. 13 is a right side view thereof;

FIG. 14 is a rear view thereof;

FIG. 15 is a left side view thereof;

FIG. 16 is a top view thereof; and,

FIG. 17 is a bottom view thereof.

The broken lines are included for the purpose of illustrating environmental structure and form no part of the claimed design.

The shade lines in the Figures show contour and not surface ornamentation.

1 Claim, 6 Drawing Sheets
